Atty.

UNITED STATES PATENT OFFICE

JOHN A. HEMRICH, OF SEATTLE, WASHINGTON

DOOR OPENER

Application filed October 8, 1927. Serial No. 224,838.

This invention relates to a method of effecting the separation of relatively movable members and more particularly to means for opening freight car doors, although certain features thereof may be employed with equal advantage for other purposes.

It contemplates more especially the provision of simple and inexpensive means for effecting the separation of relatively slideable members, which serves a special purpose in opening car doors which are usually incapable of movement with facility.

One object of the present invention is the provision of a method of gradually effecting the separation of relatively movable members.

Still another object is the provision of means for carrying a movable fulcrum capable of sustaining a member thereon to effect the separation of relatively slideable members.

A further object is the provision of a member capable of being sustained in proximity to relatively slideable members to carry a movable fulcrum which serves to sustain a bar capable of pivotal movement relative thereto to effect the movement thereof.

A still further object is the provision of a fulcrum movable relative to a carrier for the purpose of sustaining a bar effective to impart a force with mechanical advantage to a member in the path thereof to effect its movement.

Other objects and advantages will appear from the following description of an illustrative embodiment of the present invention.

In the drawing:

Figure 1 is a perspective view showing the device in its application to relatively movable members for the purpose of effecting the separation thereof.

Figure 2 is a view in elevation of the device embodying features of the present invention.

Figure 3 is a sectional view taken substantially along line III-III of Figure 2.

A method embodying features of the present invention is exemplified by the structure selected for illustration which comprises an elongated rigid member 10, in this instance

of tubular construction having a circular cross-section.

Obviously, the member 10 may be of any desired configuration as commercial practice may dictate, it having the extremities thereof provided with caps 11 and 12 to facilitate the handling thereof during its application for the purpose set forth. As shown, the cap 11 is provided with an axially disposed pointed projection 13 which is capable of penetration for the purpose of enabling the rigid member 10 to be sustained with one hand of the attendant on the cap 12 in a position substantially parallel to relatively movable members 14 and 15. The pointed projection 13 penetrates the member 14 to sustain the rigid member 10 substantially parallel thereto in proximity to the member 15 which, in this instance, constitutes a sliding door of a freight car 16.

A boss 17 of cylindrical configuration is provided with an axially disposed bore 18 somewhat greater in diameter than the member 10 to enable the sliding thereof relative thereto between the end caps 11 and 12 which serve to limit the movement thereof. The boss 17 terminates in an extension 19 having the plane surface thereof disposed substantially normal thereto, the extension 19 being provided with a bore or aperture 20 having the axis thereof disposed normal to the axis of the elongated member 10. The bore 19 serves to receive a bar or other implement 21 capable of being fulcrumed or pivoted therein so that the projecting extremity 22 thereof may be introduced between the relatively slideable members 14 and 15 to enable the separation thereof responsive to the application of force on the other extremity 23 of the bar 21. It is to be noted that the attendant may apply such force in that one hand is available for such purposes.

To prevent movement of the boss 17 relative to the rigid member 10 when the lever or bar 21 is fulcrumed therein to impart movement to the relatively slideable members 14 and 15, a lug 24 is formed integral therewith intermediate the junction of the boss 17 and an extension 19 thereof below the rigid member 10 in axial alignment therewith. The lug 100

24 serves to sustain the boss in its proper position relative to the rigid member 10 to withstand its tendency to bend occasioned by the manipulation of lever 21. It will be apparent that the surface 25 of the lug 24 will contact with the rigid member 10 to create frictional reaction therebetween to maintain the boss 17 in its proper position while the bar or lever 21 is fulcruming within the bore 20.

10 Subsequent to fulcruming the lever 21 to effect the separation of the member 15 relative to the member 14, the boss 17 is capable of being moved along the member 10 for any desired distance whereupon further separation of the member 15 is possible by manipulating the bar 21, so that repeated movement of the boss 17 followed by oscillating or fulcruming the bar 21 thereagainst will open the door step by step, thereby enabling the application of force by the human agency with much mechanical advantage.

25 Various changes may be made in the embodiment of the invention herein specifically described without departing from or sacrificing any of the advantages thereof as defined in the appended claims.

I claim:

1. A door opener comprising an elongated rigid member; a boss slidable thereon; a 30 transversely perforated rigid extension on said boss; and a lever bar passing through the perforation in said extension and engageable with a door or the like.

2. A door opener comprising an elongated rigid member having a pointed end; a boss slidable thereon; a transversely perforated rigid extension on said boss; and a lever bar passing through the perforation in said extension and engageable with a door or the like.

40 3. A door opener comprising a rigid member, a boss on said rigid member, sustaining means on said boss, a bar fulcrumed about said sustaining means for selective engagement with a door jamb to effect movement of a door in juxtaposition thereto, and means on said boss to resist the bending thereof responsive to fulcruming said bar.

45 4. A door opener comprising a rigid member adapted to be associated with a sliding door and for disposition substantially parallel thereto, a boss slidable on said rigid member, a bar fulcrumed about said boss for disposition between said door and the jamb therefor to effect movement therebetween responsive to fulcruming said bar, and means on said boss to resist the bending thereof responsive to fulcruming said bar.

5. A door opener comprising a rigid member adapted to be associated with a sliding door and for disposition substantially parallel thereto, a boss slidable on said rigid member, a bar fulcrumed about said boss for disposition between said door and the jamb therefor to effect movement therebetween re-

sponsive to fulcruming said bar, and a rib integral with said boss to effect the support thereof relative to said rigid member, and resisting bending stresses occasioned by fulcruming said bar.
